WILLIAM L. WOERNER

By Conrad A. Oelrich
his ATTORNEY

UNITED STATES PATENT OFFICE.

WILLIAM L. WOERNER, OF NEW YORK, N. Y., ASSIGNOR TO THE PROMETHEUS ELECTRIC COMPANY, A CORPORATION OF NEW YORK.

CUT-OUT FOR ELECTRIC STERILIZERS.

1,227,228.

Specification of Letters Patent. Patented May 22, 1917.

Application filed January 18, 1915. Serial No. 1,915.

To all whom it may concern:

Be it known that I, WILLIAM L. WOERNER, a citizen of the United States, residing at the city of New York, borough of Manhattan, in the county and State of New York, have invented certain new and useful Improvements in Cut-Outs for Electric Sterilizers, of which the following is a full, clear, and exact specification.

10 My invention relates to means for interrupting or breaking the electric circuit serving to energize the heating element, when the liquid within the sterilizing vessel has been completely vaporized, in order to prevent the apparatus becoming overheated or burned out.

Further, said invention has for its object to provide a cut-out with means for controlling the same, which means is actuated by 20 the heating apparatus of the sterilizer and serves automatically to discontinue the operation thereof when the apparatus becomes unduly heated in consequence of the total evaporation of the liquid in the sterilizer.

25 Further, said invention has for its object to provide a fusible cut-out comprising a fixed heat-conducting member and a removable fusible supporting element so mounted on said heat-conducting member that it will 30 control a switch whereby, when the heat rises to a predetermined temperature, said fusible support will be fused and permit the switch operating member to be released and cause the switch to break the electric circuit.

35 To the attainment of the aforesaid objects and ends my invention consists in the novel details of construction, and in the combination, connection and arrangement of parts hereinafter more fully described and then 40 pointed out in the claims.

In the accompanying drawings forming part of this specification wherein like numerals of reference indicate like parts,

Figure 1 is a side elevation of a sterilizing apparatus with one form of cut-out applied thereto constructed according to and embodying my said invention;

Fig. 2 is an enlarged detail inverted plan view of the sterilizer and the cut-out arranged thereon;

Fig. 3 is a section taken on the line 3—3 of Fig. 2 showing the switch in its normal position and the contacts actuated thereby closed;

55 Fig. 4 is a similar section showing the

switch operating member released and the switch operating means adjusted to its inoperative position and the contacts separated, and

Fig. 5 is a detail side view partly broken 60 out and in section on the line 5—5 of Fig. 2, showing the means for securing the heat-conducting member and supporting the fusible section in position thereon.

In said drawings 10 designates a sterilizing apparatus which may be of any desired shape and size, comprising a double-walled receptacle 11 having a raised bottom 12, and a hinged cover 13.

Upon the underside of the raised bottom 70 12 is secured an electric heating device comprising two series of transverse heating elements or units 14, 14' arranged alternately and held in place by longitudinal supporting members 15, 15 which are secured to the 75 underside of the bottom 12 by bolts 16, 16. 17 denotes a binding screw secured in the side of the casing 11 adjacent to its lower end. From said binding screw 17 extends a conductor 18 which is connected to each of 80 the corresponding ends of the heating units 14, 14', by clips 19, 19. 20 denotes a similar binding post from which extends a conductor 21 which is connected to the opposite 85 ends of the series of heating units 14, by clips 21', and 22 denotes a third binding post from which extends a conductor 23 which is secured to the corresponding ends of the series of heating units 14', by means of clip 23'. 90

At the side of the casing 11 directly in front of the binding posts 17, 20 and 22 is disposed a hollow block of insulating material 24 which may be made of fiber, rubber or other suitable material and secured at its opposite ends to the side of the casing by 95 brackets 25, 25, and screws 26, 26 extending through said brackets and into the opposite ends of said insulating block 24. 27 denotes a shaft which is longitudinally arranged in the support 24, and has its ends mounted in 100 the ends of said support 24. One end of said shaft 27 extends materially beyond the end of said support 24 and has an arm 28 secured at its outer end. 29 denotes a spring having its inner end disposed in a recess provided in its end of the insulating support 24, and its other end engaging the arm 28 adjacent to said shaft 27 whereby to maintain the free end of said arm normally depressed. 105

Upon the portion of the shaft 27 located 110

within the hollow block 24 are disposed eccentrics 30, 30^a which are secured in position upon said shaft by screws 31, 31.

Upon the outer surface of the insulating support 24 are secured outwardly-projecting contacts 32, 33, 34. The contact 33 is permanently connected with the binding post 17 by a conductor 33^a, while the contacts 32 and 34 are provided with contact members 32^a, 34^a which are adapted to engage with corresponding contact members 32^b, 34^b extending from the binding posts 20 and 22, respectively.

To one of the longitudinal members 15 of the heating apparatus is secured a metallic heat-conducting member 35 which extends outwardly therefrom and through the rear of the casing 11, and has its projecting portion 35^a longitudinally socketed to receive a fusible section 36 adapted to support the free end of the arm 28 fixed upon the shaft 27. The projecting portion 35^a is also provided with a cut-away portion or recess 35^b to permit of the passage of the free end of the arm 28 when the fusible supporting section 35 is fused.

37 denotes a cap of insulating material which is disposed upon, and adapted to inclose the outer end of the projecting end of the heat-conducting member 35, and the outer end of the fusible section 36 located therein.

The operation of the apparatus is as follows:

Upon connecting one conductor leading from the source of electricity with the contact 33 and the other conductor with either of the contacts 32 or 34 the current will flow through either the series of heating units 14 or the series of heating units 14'. If a less amount of heat is desired the conductors from the source of energy are connected to the contacts 32 and 34 in which case the heating units 14 and 14' will be connected in series between the conductors 21 and 23 thus decreasing the flow of the current from the source thereof.

Should the liquid within the receptacle 11 for any reason become completely vaporized the temperature of the heating apparatus will rise, and in so rising conduct the heat from said heating apparatus by means of the heat-conducting member 35 extending therefrom, and conduct sufficient heat to the projecting portion thereof to cause the fusible section 36 located therein to be fused, and as soon as this occurs the free end of the arm 28 will be caused to descend under the influence of the spring 29 arranged upon the shaft 27. As the spring 29 partially rotates said shaft 27, and the eccentrics 30, 30^a thereon the contact members 32^a, 34^a will be caused to separate from their corresponding contacts 32^b, 34^b extending from the binding posts 20, 22, and thus break the circuit.

Thereupon the supply of electric energy to the heating apparatus will be discontinued and the overheating and destruction of the receptacle 11 and the burning out or melting of the solder used thereon thereby wholly prevented.

It will be noted that although the circuit closer is shown as comprising three contacts that only two of said contact members are shown composed of a fixed element and a movable element, and that only two cams, 30, 30^a, are provided for actuating said movable contact elements. However, all of said contacts may be composed of a fixed element and a movable element and each operated by a suitable cam means upon a common shaft when it is desired positively to break the connection between each of said contacts and the source of electric supply.

Having thus described my invention, what I claim and desire by Letters Patent is:

1. In an apparatus of the character described, the combination of a receptacle, and a heater thereon, with means for controlling the supply of energy to said heater, a support on said heater, a fusible member mounted in said support for maintaining said controlling means normally in operative relation, and to release said controlling means to discontinue the supply of energy when the apparatus attains an abnormal temperature, substantially as specified.

2. In an apparatus of the character described, the combination of a receptacle, and an electric heater thereon, with means for controlling the supply of energy to said heater, means for operating said controlling means, a support secured to said heater, and a fusible member mounted in said support for maintaining the means for operating said controlling means normally in operative relation and to release said operating means to discontinue the supply of energy when the apparatus attains an abnormal temperature, substantially as specified.

3. In an apparatus of the character described, the combination of a receptacle, and an electric heater secured thereto below the base thereof, with a support secured to said heater, a fusible member mounted in said support, a circuit closer mounted upon said receptacle comprising a fixed element and a movable element, a shaft, means upon said shaft adapted to engage said movable element and to move the same into engagement with said fixed element, and an operating member for said shaft having one end free and engaged by said fusible member, whereby to hold said operating member normally in position to maintain said circuit closer operative to close said circuit, and to open said circuit closer and discontinue the supply of energy when the apparatus attains an abnormal temperature, substantially as specified.

4. In an apparatus of the character described, the combination of a receptacle, and an electric heater secured thereto and arranged below the base thereof, with a support 5 port secured to said electric heater, a fusible member in said support, a circuit closer comprising a base, a fixed contact member, a movable contact member, a shaft mounted in said base, a cam thereon serving to move 10 said movable contact member into engagement with said fixed contact member, an arm on said shaft having its free end normally supported upon said fusible member whereby to maintain said circuit closer operative to permit of the flow of energy to 15 said heater, and spring means to actuate said shaft and cam to break the engagement of said contact members whereby to discontinue the supply of energy when the apparatus 20 attains an abnormal temperature, substantially as specified.

5. In an apparatus of the character described, the combination of a receptacle, and an electric heater comprising a plurality of 25 elements secured thereto and arranged below the base of said receptacle, with a support secured to said heater and extending laterally therefrom, a fusible member mounted in said support, a circuit controller comprising 30 a base secured to said receptacle, a fixed contact member connected with one terminal of each of said heater elements, a fixed

contact member connected with the opposite terminals of certain of said heater elements, and a fixed contact member connected with 35 the opposite terminals of the others of said heating elements, movable contact members secured to said base adapted to engage with the fixed contacts connected with the two series of opposite terminals of said heating 40 elements, a shaft mounted in said base, cams on said shaft adapted to engage said movable contact members and move the same into engagement with their respective fixed contact members, an arm on said shaft having its free end normally supported upon 45 said fusible member whereby to maintain said cams in position to hold said movable contact members in engagement with their respective fixed contact members whereby 50 to permit of the flow of energy to said heater elements, and to discontinue the supply of said energy when the apparatus attains an abnormal temperature, substantially as specified.

Signed at the city of New York, in the county and State of New York, this 14th day of October, one thousand nine hundred and fourteen.

WILLIAM L. WOERNER.
